UNITED STATES PATENT OFFICE.

CHARLES EDWIN SEARCH AND JOSEPH W. MOORE, OF MILWAUKEE, WISCONSIN,
ASSIGNORS TO ALLIS-CHALMERS MANUFACTURING COMPANY, OF MILWAUKEE,
WISCONSIN, A CORPORATION OF DELAWARE.

STEAM-TURBINE.

1,187,453.

Specification of Letters Patent. Patented June 13, 1916.

Application filed August 13, 1913, Serial No. 784,779. Renewed September 20, 1915. Serial No. 52,113.

To all whom it may concern:

Be it known that we, CHARLES EDWIN SEARCH and JOSEPH W. Moore, citizens of the United States, residing at Milwaukee 5 and West Allis, Milwaukee, respectively, in the county of Milwaukee and State of Wisconsin, have invented a certain new and useful Improvement in Steam-Turbines, of which the following is a specification.

10 This invention relates to improvements in steam turbines and more especially to a segment of blades designed for insertion in or attachment to the spindle or cylinder of a steam turbine, and which is to be produced 15 as a finished article of manufacture capable of withstanding the severe vibration stresses to which it will be subjected in the machine.

20 The object of the invention is the production of a segment of blades for a turbine, which avoids the defects of the prior art 25 structures, more especially being constructed to withstand vibration stresses.

25 Referring to the drawings, Figure 1 is a plan view of a segment of turbine blades, the shroud strip being partly broken away. Fig. 2 is an elevation of same. Fig. 3 is a 30 sectional view of a portion of a segment of blading, the section being taken in a plane of rotation. Fig. 4 is a transverse sectional view of same showing the detail of the securing means to the spindle or cylinder of the turbine.

35 In actual practice it has been found that a steam turbine constructed with segments 40 of blades calked in the spindle and cylinder, and having shroud strips fastened to the ends of the blades by riveting-over integral tenons formed on the ends of the blades and preliminarily inserted through holes 45 punched therefor in the shroud strips,—has not been able to withstand the vibration stresses imposed on the built-up structure by reason of the high speeds at which the turbine was designed to run. The result was 50 disastrous and the blades became detached.

55 As the result of an exhaustive study of the conditions entering into the construction and operation of such turbines, it has been found by actual test that there is a definite 60 law controlling the pitch of vibration of the built-up structures.

A segment of turbine blades made up with a Sankey foundation strip and with a

riveted shroud strip as hereinbefore referred to, was fastened securely in a vise at its 55 foundation strip, a vibratory tachometer was placed on the segment of blades so held and the segment was then vibrated manually by quickly running a piece of hard material over the blades in much the same 60 manner as a boy would run a stick along a picket fence. The tachometer gave a certain reading for the pitch of the vibration thus produced, which reading it is unnecessary to state here in actual figures. A similar 65 segment was experimented with in the same way, except that the foundation strip was cast-on to the ends of the blades, as a substitute for the Sankey foundation strip. When vibrated, the reading of the tachometer 70 was substantially higher. Next, a similar segment with the foundation strip cast-on was taken, but the shroud strip in this case, was soldered to the ends of the blades. Upon test, the tachometer again recorded a substantially higher figure as 75 representing the pitch of vibration. Lastly, a tie-strip was soldered at one side of the segment of blades, intermediate their ends, the foundation strip being cast-on and the shroud strip being soldered on, and the tachometer in this case again indicated a substantially higher figure than before.

80 This investigation clearly indicated the theory upon which the present invention is 85 based. It has been found, in one case, where the blades had "gone out" on a turbine, where the shroud strip had been riveted on and without any tie-strip, that the vibration tachometer in a test of similar 90 segments of blading to those used in that turbine, indicated substantially the same figure for pitch of vibration as the speed itself of the turbine. In other words, the pitch of vibration of the segment was in resonance 95 with the speed of the machine, a condition highly objectionable and as heretofore pointed out, actually disastrous in practical operation. It is believed, as based upon these experiments, that the vibration of the 100 blade segments is brought about by the elastic construction resulting from the many different mechanical fastenings of the prior art. It is believed that the trailing ends of the shroud strips, if not the trailing ends 105 of the segment itself, whip during rotation,

in much the same way as a flag whips in the wind. It was therefore found that a stiff and rigid, but comparatively inelastic, truss-like segment of blades is what is necessary 5 to avoid this objectionable vibration and to raise the pitch of vibration safely beyond the speed of the turbine, so as not to be in resonance therewith. It is found that the casting-in of the blades in the foundation 10 strip, resulting in a softening and annealing of the blade near the cast-on foundation strip, is an important factor toward arriving at the accomplishing of the object of this invention. Soldering a tie-strip to the 15 blade at an intermediate point, and soldering a shroud strip at the end of the blade, are equally important factors for the attainment of this result. Absence of any 20 projections whatever at the shroud strip fastening, such for instance as the riveted-over tenon ends of the prior art, it is believed additionally prevents the tendency to set up objectionable vibration. Incidentally it might be stated that in the prior 25 art riveting-over of the tenon to fasten the shroud strip causes either looseness, or distortion of the shroud strip itself, in the case where a blade happens to be slightly shorter than it ought to be; and this 30 looseness is, of course, an element productive of vibration while the distortion of the shroud is objectionable for other reasons, primarily failure to baffle properly; additionally, the rivet heads serve as paddle 35 brakes during rotation.

It is understood that, in the prior art, a structure has been proposed to which thin supporting strips have been welded to the blades and then stout stiffening rings have 40 been soldered to the strips, or equivalent fastening means have been used, but in all of these constructions the stout stiffening ring is always present in addition to the thin supporting strip. If these were used 45 in an axial flow turbine with which the present invention primarily deals, although it is as well applicable to a radial flow turbine, it would be impossible on account of the heavy structure to practicably baffle the 50 leakage flow of steam around the ends of the blades of the segments, which the shroud strip in the present invention is designed to accomplish. The weight of this heavy structure is supported from the blades and 55 this is objectionable on account of the excessive centrifugal force during rotation. It should also be pointed out that those proposed constructions are primarily applicable to gas turbines of the radial flow type. 60 In such a turbine very high temperatures exist and soldering must be exceedingly questionable as a practicable fastening. Also in the prior art is to be found a turbine having a few end blades of a segment brazed 65 to a shroud strip, but there the segment is

mechanically fastened to the foundation strip, and moreover the shroud strip is located adjacent the ends of the blades leaving projecting blade ends to objectionably serve as paddles during rotation. Also, it 70 has been proposed to cast-on both foundation strip and shroud strip, but in such construction the shroud strip would be entirely too heavy to serve as a baffle to prevent leakage of steam and its weight supported from the blades would be objectionable; it would also be not uniform in texture if cast thin enough to be a practicable baffle.

Referring more particularly to the drawing, a series of blades 1 is shown cast-in 80 in the foundation strip 2, and has fastened to its ends a single, light shroud strip 4, by soldering the parts directly together. This mode of securing the shroud strip is preferable to welding as it is difficult to prevent 85 distortion of the parts in order to make a weld, whereas such a high heat is not necessary in soldering. The solder 5 is clearly shown in Figs. 3 and 4. The light shroud strip 4 is indicated as punched with holes of 90 shape corresponding to tenons 6 formed on the ends of the blades by cutting away the side portions of the ends of the blades, leaving the tenon 6 preferably with two parallel sides and two sides with a curvature corresponding to the surface of the blades. These tenons 6 are short, preferably only of sufficient length to fairly enter the holes punched in the shroud strip 4. They are 95 shown of length equal to the thickness of the shroud strip 4 so as to be flush with the 100 surface of the shroud strip between the sides of the channel, which shape the shroud strip 4 assumes. The object of extending the tenons 6 into correspondingly shaped 105 holes in the shroud strip 4 is twofold, first, to properly space the blades, and second, to properly set the same at their theoretical angle about their axes. The strip having 110 been properly set against the extreme ends of the blades 1, the same is soldered thereto preferably by placing the segment of blades in a position where the shroud strip 4 is at the bottom; but, in the case of very small blades set close together, the segment may 115 be so placed as to have the shroud strip 4 at the top and the solder 5 may be applied through the interstices between the tenons and the holes in the shroud strip. It is, however, to be distinctly understood that it 120 is not necessary that there be any soldering of the tenon within the hole in the shroud strip, as it has been found by test that the soldering of a straight ended blade directly to a shroud strip produces a fastening 125 strong enough to rupture the blade itself before pulling off the shroud strip. After soldering the shroud strip 4 to the ends of blades 1, the structure about this fastening is then a smooth surface throughout the 130

full extent of the shroud strip. This is important as presenting no paddle brake action during rotation.

A tie-strip 7 is soldered to the blades 1 at a point intermediate thereof, and preferably in notches provided in the blades. This feature alone, is not, of course, intended to be represented as novel. This strip may be omitted in the case of short 10 blades or where the speed is comparatively low.

The segment of blades as thus far constructed, is then machined as to its foundation strip 2 and the shroud strip 4, so as 15 finally to produce an article of manufacture which is applicable to a turbine spindle or cylinder without any further machining. The finished segment is designed to be calked into a recess formed in the spindle or 20 cylinder 3 of the steam turbine, as indicated in Fig. 4.

It should be understood that it is not desired to be limited to the exact details of construction shown and described, for obvious 25 modifications will occur to a person skilled in the art.

It is claimed and desired to secure by Letters Patent,—

1. The combination of a plurality of 30 blades, a cast-on foundation strip for said blades, a single shroud strip soldered to the extreme ends of said blades, a tie strip soldered to intermediate portions of said blades, and means for fastening said foundation strip to a support.

2. The combination of a plurality of 40 blades, a cast-on foundation strip for said blades, a shroud strip soldered to the extreme ends of said blades, a tie strip soldered to intermediate portions of said blades, and means for fastening said foundation strip to a support.

3. The combination of a plurality of 45 blades, and a foundation strip, a single light shroud strip, and a tie strip each united to said blades by fusion of metal, and means

for fastening said foundation strip to a spindle or cylinder.

4. As an article of manufacture, a segment of blading having a foundation strip, 50 a single light shroud strip and a tie strip each secured to said blading by fusion of metal.

5. As an article of manufacture, a segment of blading having a foundation strip 55 cast-on, a shroud strip soldered to the extreme ends of said blading and a tie strip soldered to intermediate portions of said blading.

6. As an article of manufacture, a segment of blading having a foundation strip, a single light shroud strip and a tie strip each secured to said blading by fusion of metal and said shroud strip being smooth throughout at its connection to said blading. 65

7. As an article of manufacture, a segment of blading having a foundation strip cast-on, a shroud strip soldered to the extreme ends of said blading and a tie strip soldered to intermediate portions of said 70 blading, said shroud strip being smooth throughout at its connection to said blading.

8. As an article of manufacture, a segment of blading having a foundation strip and a previously formed single light shroud 75 strip each secured to said blading by fusion of metal and said shroud strip being smooth throughout at its connection to said blading.

9. The combination of a plurality of blades, a cast-on foundation strip for said 80 blades, a previously formed shroud strip soldered to the extreme ends of said blades, and means for fastening said foundation strip to a support.

In testimony whereof, the signatures of 85 the inventors are affixed hereto in the presence of two witnesses.
